UNITED STATES PATENT OFFICE.

ALGENON S. SPAULDING, OF BLOOMSBURG, PENNSYLVANIA.

FLEXIBLE-CURTAIN CONSTRUCTION.

SPECIFICATION forming part of Letters Patent No. 634,072, dated October 3, 1899.

Application filed April 4, 1898. Serial No. 676,276. (No model.)

To all whom it may concern:

Be it known that I, ALGENON S. SPAULDING, a citizen of the United States, residing at Bloomsburg, in the county of Columbia and State of Pennsylvania, have invented a new and useful Flexible-Curtain Construction, of which the following is a specification.

My invention relates to that class of flexible rolling or coiling partitions which are formed by a series of connected slats; and one object of my invention is to diminish the friction, wear, and noise incidental to this class of partitions by constructing and mounting the slats which constitute the partition so that they will turn on knife-edge joints with respect to each other and present finished surfaces free from cracks or projections.

A further object of my present invention is to locate the flexible connections which bind the slats together so that the tension of such flexible connections will tend to keep the slats normally straightened out or in line with each other.

A further object of my invention is to provide means so that the slats will not shift or move endwise with respect to each other.

Flexible partitions which have heretofore been formed of wooden slats or strips and which have been used for flexible curtains, shutters, doors, desk-tops, &c., have heretofore ordinarily been constructed or formed in two manners. In one form of construction—such, for example, as is used in the ordinary roll-top desk—the slats or strips are pasted or secured on a canvas or other flexible backing.

A construction of this nature presents but one finished surface and cannot ordinarily be used where both sides of the partition are exposed to view. In a second class of construction the slats or strips have been formed with a rounding socket on one edge and with a rounding bead in the opposite edge for engaging the socket of the adjacent strip. In practice I have found that the rolling joints between slats which are fitted together in this manner present considerable frictional resistance to the operation of the flexible partitions, and this especially is true if any of the slats become warped or distorted to a slight degree. Furthermore, the edges of the slats, turning and rubbing on each other, in this construction wear upon each other to an extent that

is undesirable. To obviate these objections and to provide a flexible partition which can be rolled or coiled with substantially no frictional resistance and still present finished surfaces free from cracks or projections, I mold or shape the slats so that in addition to rounding beads and corresponding sockets the slats are also provided with angular grooves and corresponding projections, which permit them to turn with respect to each other on substantially knife-edge joints.

A further object of the invention is to provide improved adjustable connecting mechanism for the slats and means for keeping the slats from shifting endwise, which constructions will be detailed in the following specific description.

In the accompanying drawings, Figure 1 is a perspective view of a section of flexible partition constructed according to my invention. Fig. 2 is an enlarged view illustrating the construction of the slats. Fig. 3 is a similar view illustrating the slats tipped or turned to a different relative position. Fig. 4 is a sectional elevation through the slats. Fig. 5 is a rear view of the last or end slat. Fig. 6 is a detail view, on a still further enlarged scale, of the preferred means for keeping the slats from shifting endwise. Fig. 7 is a view similar to Fig. 6, illustrating a modification; and Fig. 8 is a sectional view illustrating a modified form of means for connecting the slats.

Referring to the drawings and in detail, a flexible partition constructed according to my invention, as illustrated in Fig. 1, comprises a plurality of similar slats *a*. As most clearly shown in Figs. 2 and 3, each of the slats *a* is provided at one edge with a rounding bead *10* having a V-shaped groove *10* and at its opposite edge with a corresponding socket having an angular or knife-edge projection *11* for engaging the socket or groove in the adjacent slat. As illustrated in the drawings, each of the angular projections *11* is formed substantially at an angle of forty-five degrees, so that the inclined side thereof will engage and rest against one side of the groove *10* in the adjacent slat when the slats are straightened out into substantial line with each other, as shown in Fig. 2—that is, the groove *10* is made about ninety degrees, more or less, forty-five degrees on each side of a plane passing through

the center of the slats, and the projections 11 are made with one side parallel to or included in this central plane and the other side inclined at about forty-five degrees thereto, this 5 construction permitting the slats to tilt forty-five degrees relatively to one another. Of course these angles may be varied to suit the exigencies of any particular construction.

By means of this construction it will be seen 10 that when the partition is straightened or unrolled to its closed position the sides of the projections 11, engaging the sides of the grooves 10, will form a tight joint throughout the length of the door. It will also be seen 15 that as the slats turn one on the other the knife-edges 11 will rotate in the bottoms of the grooves 10 and that this action takes place with substantially no friction. It is also to be noticed that the center of motion of each 20 knife-edge joint is substantially concentric with the rounding bead, so that no cracks or projections will be presented on the surfaces of the door.

At its bottom or front end the flexible partition 25 is generally provided with a heavy bottom strip *b*, which may have a number of hand-holes or sockets *c* for operating the partition, it being understood that the partition may be rolled up by any suitable means, as a coiled 30 spring, substantially in the same manner that a curtain is coiled on the ordinary Hartshorn roller, or the door may be folded, rolled, or otherwise deflected either horizontally or vertically in any of the usual manners, my present 35 invention being directed rather to the shape and manner of connecting the slats together than to any particular manner of mounting and operating the flexible partition.

To secure or string the slats together, I may 40 employ any of the usual flexible connections, such as steel strips, wire cords, &c.; but the preferred construction is shown in Fig. 4. In this construction a number of wire cords *d* are passed through holes bored in the slats *a* 45 slightly at one side of the projections 11 and the corners of the grooves 10, as shown in Fig. 2. By stringing the slats together in this manner I have found in practice that by locating the flexible cords or connections in this position 50 the tension placed on the cord will normally tend to straighten the slats with respect to each other and keep them in line, which will insure the door presenting a smooth appearance when closed. One end of each cord 55 *d*, which is generally made of twisted wire, is unraveled, bent back, and dipped in solder, so as to have a bullet-like head *d*². This bullet-like head is placed in the bottom of a screw-threaded bushing 12, which is fitted in the bottom 60 piece *b*, this bushing having a knife-edge or key 13 for preventing the same from turning therein. A screw 14 is tapped in the other end of the bushing 12, and the head of said screw engages a washer 15, set in the bottom 65 piece *b*. The other end of each cord is tapered down and dipped in solder, so that the same will have a needle-like finish *d*'. This enables

me to readily thread the cords through the slats. This end of each cord is then bent down and secured by heavy staples 16 and 17 to the rear side of the last slat *a*, as shown in Fig. 5. By means of this construction by manipulating the screws 14 the cords can be tightened and the slats kept in proper relation one to the other and any wear between the slats thus 75 taken up.

In some cases—as, for example, when the door is used vertically—it may be desirable to use additional means to prevent the slats from shifting endwise relatively to one another. To accomplish this purpose, I drill holes through all the slats and drive therein pins 18, which have their ends slabbed or milled off, so as to have half-round projections 19 19 on the ends thereof. These pins 18 are 80 arranged in the slats as shown in Fig. 4, the projecting slabbed end of the pin in one slat engaging the slabbed end of the pin in the next slat. The projecting slabbed heads 19 19 are oppositely disposed on the pins, as shown 85 in Fig. 6. As many of these pins are used as desired. It will be seen that these pins will act to prevent any endwise shifting of the slats.

A modified form of pin is shown in Fig. 7, 90 the same being made out of a half-round piece of steel 20, which is twisted so that its ends will be oppositely disposed to accomplish the functions of the oppositely-disposed slabbed heads 19 19 of the pin 18.

Instead of employing the flexible rope or cord I may employ a construction comprising a series of hinge-joints, such as is described and claimed in Letters Patent No. 558,577, granted to me April 21, 1896, and I have illustrated such a construction in Fig. 8. As shown in this figure, each of the hinge-bolts 21 is milled or cut away near one end to form a projecting pintle 23, and at its opposite end each hinge-bolt is provided with an offset 100 flattened section 22, having a socket for receiving the pintle of an adjacent hinge-bolt. When the slats of my improved flexible partition are to be strung together by the use of my hinge-bolt, I prefer to locate the hinge-bolts exactly in the middle of the slats; but said hinge-bolts may, if desired, be located 105 slightly at one side thereof.

I am aware that changes may be made in the construction of my flexible partition by 110 those who are skilled in the art without departing from the scope of my invention as expressed in the claims. I do not wish, therefore, to be limited to the form which I have shown and described; but

What I do claim, and desire to secure by Letters Patent of the United States, is—

1. As an article of manufacture a flexible partition comprising a plurality of slats having rounding beads for engaging corresponding sockets in adjacent slats, each bead having an angular groove and each socket having an angular projection for engaging said groove, so that said slats may turn with re-

spect to each other substantially on knife-edge joints, substantially as described.

2. As an article of manufacture, a flexible partition comprising a plurality of similar slats, each having along one edge a rounding bead with a V-shaped socket or groove, and along the other edge a corresponding socket with an angular projection to engage the groove in an adjacent slat to form substantially knife-edge joints between the slats, the inclined side of each projection engaging the side of the groove into which it fits when the slats are in line with each other, substantially as described.

15 3. In a flexible partition, the combination of a plurality of slats, each having a rounding bead with an angular groove formed on one edge and on its opposite edge a corresponding socket having an angular projection, and flexible connections extending through said slats at one side of the knife-edge joints formed by said grooves and projections so that the tension of the flexible connections will tend to keep the slats in line with each other, substantially as described.

4. In a flexible partition, the combination of similar slats *a*, each having a rounding bead with a rectangular groove or socket 10 along one edge thereof, and on the opposite edge a corresponding socket having a forty-five-degree angular projection 11, the inclined side of the projection 11 engaging the side of the groove 10 into which it fits when the slats are in line with each other, and flexible cords *d* extending through said slats at one side of the knife-edge joints formed by the grooves 10, and projections 11, so that the tension of the flexible cords will tend to keep the slats in line with each other, substantially as described.

5. In a flexible partition, the combination of a plurality of slats and wire cords for stringing said slats together, each of said wire cords being twisted or braided from a plurality of strands, and the stringing end of each of said cords being soldered and tapered to form an integral needle-like section or point to facilitate threading the slats off said cords, substantially as described.

50 6. In a flexible partition, the combination of a plurality of slats, means for hinging or stringing said slats together, and a plurality of pins secured in said slats and having plane or flat engaging surfaces for preventing the slats from shifting endwise relatively to one another, substantially as described.

7. A flexible partition comprising a plurality of slats, means for stringing or hinging said slats together, and means for preventing said slats from shifting endwise relatively to one another, comprising pins 18 having oppositely-arranged slabbed heads 19, substantially as described.

8. In a flexible partition the combination of a plurality of slats having rounding beads 65 engaging corresponding sockets in adjacent slats, each of said beads having an angular groove therein, and each socket having an angular projection and wire cords for stringing said slats together, the stringing end of 70 each cord being soldered and tapered to form a needle-like point, substantially as described.

In testimony whereof I have hereunto set my hand in the presence of two subscribing witnesses.

ALGENON S. SPAULDING.
